UNITED STATES PATENT OFFICE.

FRANCESCO MONTIGLIO, OF CHESTER, PENNSYLVANIA.

PLEASURE-BOAT.

1,314,969.

Specification of Letters Patent.

Patented Sept. 2, 1919.

Application filed June 10, 1919. Serial No. 303,011.

To all whom it may concern:

Be it known that I, FRANCESCO MONTIGLIO, a citizen of Italy, residing at Chester, in the county of Delaware and State of Pennsylvania, have invented a new and useful Pleasure-Boat, of which the following is a specification.

This invention has reference to pleasure boats, and its object is to provide a boat arranged to be propelled by the efforts of the occupant or occupants of the boat, the hull of the boat being of the catamaran type, whereby there is offered but little resistance to the progress of the boat by the water, but the boat is particularly stable.

In accordance with the invention, the boat is provided with two connected hulls in parallel relation and suitably spaced apart to give ample beam, whereby danger of capsizing is practically eliminated so that the occupants of the boat may be considerably elevated above the level of the deck of the boat, thereby avoiding wetting the occupants, of which there are usually two, while the beams of the individual hulls are narrow and consequently the boat may make its way through the water with relatively little resistance from the water.

The invention contemplates the use of a bicycle drive and continuously driven ratchet mechanism imparting rotative movements to a propeller.

The invention will be best understood from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of the invention as expressed in the appended claims.

In the drawings—

Figure 1 is a side elevation of a boat embodying the invention.

Fig. 2 is a plan view thereof.

Fig. 3 is a rear elevation with some parts broken away and certain distant parts omitted.

Fig. 4 is a vertical cross section about midway the length of the boat, but omitting numerous parts.

Fig. 5 is an elevation of an elongated lever forming part of the driving mechanism.

Fig. 6 is a section on the line 6—6 of Fig. 1, but drawn on a larger scale and confined to certain details of the structure.

Referring to the drawings, there are shown two boat hulls 1, 2 which may be solid or hollow, but preferably made hollow and follow ordinary outlines except that the hulls are long with respect to their beam and may be quite straight along the sides so that the resistance of the water to the forward movement of the hulls is reduced to a minimum. The hulls are held in parallel spaced relation by cross beams 3 at suitable points along the length of the vessel, and these beams may be utilized to support propelling structure in most part over the space between the hulls.

Erected on the forward cross beam 3 are spaced journal bearings 4 carrying a shaft 5 on which are secured a sprocket wheel 6 and a crank disk 7, which parts, however, may be replaced by equivalent structures. Erected on other cross beams 3 to the rear of the forward cross beam 3 are posts 8, 9, it being understood that the boat, as shown in the drawings, is designed to carry two operators, but it will be further understood that if a greater number of operators is desirable the boat may be correspondingly elongated and more posts may be provided. The upper ends of the posts are connected by a longitudinally disposed beam 10 fast to the respective posts and provided with a forward projection 11 carrying an upright steering shaft 12 journaled in the projection 11 and provided above such projection with a steering wheel 13. The lower end of the shaft 12 has a step bearing in an appropriate one of the cross beams 3.

Near the lower end of the shaft 12 it has fast to it a pinion 14 meshing with a rack 15 on the forward end of a bar 16 extended to the stern of the boat and there provided with another rack 17 projecting beyond the stern of the boat and engaging a pinion 18 on the post 19 of a rudder 20. To support the rudder there is provided a bracket 21

made fast to and projecting from the rear cross bar 3, or this bracket may be supported in any other appropriate manner, the arrangement being such that upon turning the 5 steering wheel 13 the rudder may be moved to one side or the other, or may be held straight ahead in the longitudinal center line of the structure. The bracket 21 carries a guide 22 for the rear rack 17 and 10 other guides may be provided, wherever advisable, along the length of the bar 16.

Carried by the posts 8 and 9 at a lower level than the bar 10 are other longitudinally arranged bars 23 in parallel relation, 15 as shown in Fig. 4. Journaled in the bars 23 and extending transversely thereof are crank shafts 24, 25, each provided with cranks 26 and foot pedals 27 which may be of the usual bicycle type. The crank 20 shaft 24 carries a sprocket wheel 28 and the crank shaft 25 carries a sprocket wheel 29. Extending between and engaging the 25 sprocket wheels 6, 28 and 29 is a sprocket chain 30 for transmitting motion from the crank shafts 24 and 25 to the shaft 5 and from the latter to the crank disk 7.

Near the stern of the boat structure there is a shaft 31 extending from one boat to the other across the intervening space and 30 supported by brackets 32 on the respective boats at their adjacent faces. The brackets 32 may be utilized for stiffening the post 9 through brace bars 33, each fast at one end to a respective bracket 32 and at the 35 other end to the rear end of the post 9 close to the upper end thereof. The shaft 31 carries two ratchet wheels 34, 35 respectively, and intermediate of the ratchet wheels the shaft 31 has mounted thereon a hub end 36 40 of a lever 37, shown separately in Fig. 5. This lever extends through slots 38 in the posts 8 and 9, the slot in the post 9 not being shown in the drawings but corresponding to the slot 38 and the post 8. The lever 45 37 is continued forwardly to the crank disk 7 and is there connected to the crank disk by a link 39. At intermediate points in the length of the lever 37 are lateral extensions 40, 41, in which are formed slots 42, 43 respectively, curved on an arc of which the axis of the hub 36 is the center. The slots 42 and 43 are so located as to be traversed by the crank shafts 24 and 25 respectively, thus permitting the lever to rise and fall 50 about the shaft 31 as an axis to an extent determined by the size of the crank disk 7.

Mounted on the post 8 is an operator's seat 44 and mounted on the post 9 is an operator's seat 45. The seat 44 is adjacent to the 60 steering wheel 13 and the seat 45 may have adjacent to it on the beam 10 a handle bar 46 similar to a bicycle handle bar.

The ratchet wheels 34 and 35 have their

teeth on the outer faces adjacent to the outer periphery and the teeth of one wheel are oppositely directed to those of the other wheel. On the inner face of each wheel 34 and 35 is a circular series of bevel gear teeth 47 meshing with a bevel pinion 48 on opposite sides of the latter. The pinion 48 is fast to 70 a shaft 49 journaled in a bracket 50 fast to the stern portion of the two boat hulls and extending from one to the other. Fast on the shaft 49 is a sprocket wheel 51 connected by a sprocket chain 52 to a sprocket pinion 53 75 on a short propeller shaft 54 carrying a propeller wheel 55 at its outer end and mounted in a journal bearing 56 supported by arms 57 rising in divergent relation and made fast to the rear or stern end of the boat hulls 1 80 and 2.

The lever 37, at a point removed from the hub 36 by a distance somewhat greater than the radius of the ratchet wheels 34 and 35, is traversed by a rod or bar 57^a. Pendently 85 carried by the bar 57^a are pawls 58, 59, urged toward each other by a spring 60 common to both. The pawl 58 at its lower end is provided with a lifting tooth 61 and the pawl 59 is provided at its lower end with a pushing tooth 62. The ratchet wheels 34 and 35 have correspondingly arranged teeth 63 and 64 respectively. The arrangement is such that when the pawl 58 is raised the tooth 61 will engage a tooth 63 and turn the ratchet 95 wheel 34 in one direction while the pawl 59 pushes the ratchet wheel 35 in the opposite direction. Since both ratchet wheels engage the pinion 48 on opposite sides thereof, the alternating movements of the ratchet wheels 100 in opposite directions cause a continuous movement of the pinion in one direction, which is the direction to propel the boat forwardly through the sprocket wheel 51, chain 52, sprocket wheel 53, shaft 54 and propeller 55. 105

Two operators occupying the seats 44 and 45 may readily actuate the sprocket chain 30 and by way of the lever 37 cause the rotation of the ratchet wheels 34 and 35 oppositely with a step-by-step motion, which, however, is translated into a continuous rotary motion by the pinion 48 transmitting like motion to the propeller 55. The operator using the seat 44 is enabled to steer the 110 vehicle by means of the steering wheel 13, shaft 12, pinion 14, racks 15 and 17 of the bar 16, pinion 19 and rudder 20. The steering wheel 13 also acts as a steadyng means for the operator occupying the seat 44. The 115 operator occupying the seat 45 is steadied by the handle bar 46.

The arrangement is such as to utilize the propelling power of a plurality of operators and this may be done as easily as two operators can propel a tandem bicycle, except 125

that the resistance of the water renders the work somewhat heavier. The boat will travel more steadily than a tandem bicycle, since no balancing is required because of the 5 wide beam of the vessel due to its catamaran characteristics.

What is claimed is:—

1. A pleasure boat comprising a catamaran body with the boats or hulls spaced apart, steering and propelling means rising above the deck level of the pleasure boat and comprising a framework having operators' seats spaced apart lengthwise of the boat, a steering wheel adjacent to one seat and a 10 handle bar adjacent to the other seat, pedal crank shafts carried by the frame in position to be actuated by operators on the seats, sprocket wheels on the crank shafts, a crank disk at the forward end of the boat and provided with a sprocket wheel, a sprocket chain engaging all the sprocket wheels, a 15 transverse shaft at the rear portion of the boat, combined ratchet and gear wheels on the last-named shaft, a rock lever mounted 20 at one end on the last-named shaft and at the other end connected to the crank disk, pawls carried by the lever and engaging both ratchet wheels to cause step-by-step alternate rotation of the ratchet wheels in 25 opposite directions, a propeller, and one-way connections between the combined ratchet and gear wheels and the propeller.
2. A pleasure boat comprising a catamaran body with the hulls spaced apart, 30 propelling means rising above the deck level of the boat intermediate of the hulls, operators' seats on the framework spaced apart in the direction of the length of the boat, the propelling means including bicycle 35 crank shafts with pedals carried by the frame to be actuated by operators on the seats, and a crank disk connected to and propelled by the crank shafts, an elongated rock lever extending from the crank disk toward 40 the stern of the boat and there pivoted and provided with transverse slots in turn traversed by the pedal shafts, ratchet wheels concentric with the pivoted end of the rock lever and each having a circular series of 45 gear teeth thereon facing those of the other, the ratchet wheels having their teeth oppositely directed, oppositely acting pawls carried by the rock lever and engaging the ratchet therewith, a gear pinion engaged by 50 the gear teeth of the two wheels, and a propeller shaft connected to the pinion.

3. A pleasure boat comprising a catamaran body, and propelling means therefor carried by the body above the deck level 55 thereof and comprising tandem operators' seats and pedal cranks, a rock lever mounted to move about an axis parallel with the deck of the boat, with the operators' seats located

intermediate of the length of the lever, connections between the pedal crank shafts and 65 the lever at the end thereof remote from its pivot, step-by-step mechanism propelled by the lever, a propeller carried by the boat below the water level, connections between the propeller and mechanism above the deck 70 level of the boat, and translating means between the last-named means and the step-by-step means whereby the movement of the step-by-step means is converted into continuous progressive movement of the means 75 connected to the propeller.

4. A pleasure boat comprising a catamaran body, a propeller located below the water level of the boat, and propelling means located above the deck level of the 80 boat and comprising a plurality of operators' seats and pedal crank shafts associated therewith, the seats and shafts being spaced apart lengthwise of the boat, a rock lever mounted near the rear end of the body 85 of the boat to move on an axis substantially parallel with the deck of the boat crosswise of the latter, connections between the pedal crank shafts and the other end of the lever for imparting an up and down reciprocation 90 thereto, driving means for the propeller extending to a level above the deck level of the boat, and means for converting the rocking movement of the lever into continuous rotative movement of the propeller. 95

5. A pleasure boat comprising a catamaran body, a propeller located below the water level of the boat, and propelling means located above the deck level of the boat and comprising a plurality of operators' seats and pedal crank shafts associated therewith, the seats and shafts being spaced apart lengthwise of the boat, a rock lever mounted near the rear end of the body 100 of the boat to move on an axis substantially parallel with the deck of the boat crosswise of the latter, connections between the pedal crank shafts and the other end of the lever for imparting an up and down reciprocation 105 thereto, driving means for the propeller extending to a level above the deck level of the boat, and means for converting the rocking movement of the lever into continuous rotative movement of the propeller, the driving means for the propeller extending above the 110 deck level of the boat having motion multiplying characteristics. 115

6. A pleasure boat comprising a catamaran body, a propeller at the stern thereof and below the water level of the body, and 120 driving means for the propeller located above the deck level of the body and comprising tandem operators' seats, tandem pedal crank shafts, one for each seat, a crank disk at the bow end of the boat connected to 125 and driven by the pedal crank shafts, a rock

lever connected at one end to the crank disk and at the other end pivotally mounted near the stern of the boat to rock on an axis parallel to the deck of the boat and transversely 5 thereof, said lever being provided with elongated slots lateral to the length of the lever and traversed by the crank shafts, and means connected to the rock lever and to the propeller for converting the rocking move-

ments of the lever into continuous rotary movement of the propeller.

In testimony that I claim the foregoing as my own, I have hereto affixed my signature.

FRANCESCO MONTIGLIO.
